CLAIM

The ornamental design for an orthodontic anchorage screw, as shown and described.

DESCRIPTION

FIG. 1 is a perspective view of an orthodontic anchorage screw showing our new design;

FIG. 2 is a top plan view thereof;

FIG. 3 is a bottom plan view thereof;

FIG. 4 is a front elevation thereof, the side opposite being substantially a mirror image thereof; and,

FIG. 5 is a left side elevation thereof view, the side opposite being substantially a mirror image.
